UNITED STATES PATENT OFFICE.

ANTHONY CHIARELLI, OF NEW YORK, N. Y.

AEROPLANE-STABILIZER.

1,340,214.

Specification of Letters Patent. Patented May 18, 1920.

Application filed March 2, 1918. Serial No. 219,955.

To all whom it may concern:

Be it known that I, ANTHONY CHIARELLI, a citizen of the United States of America, residing at New York city, county and State of New York, have invented certain new and useful Improvements in Aeroplane-Stabilizers, of which the following is a full, clear, and exact description.

This invention relates to improvements in stabilizing devices for aeroplanes, the object being to provide an automatically acting device, that will maintain the aeroplane in a horizontal position; that is to say, a device which will act to restore the aeroplane to a horizontal position should it for any reason dip on one end or the other.

To carry my invention into practice, I place a propeller, at each end of the plane, said propellers being disposed in a horizontal position and each acting to force its respective end of the plane upwardly should said end dip to an undesirable extent, special means being provided to control the operation of the propellers.

I will now proceed to describe my invention in detail, the novel features of which I will point out in the appended claims, reference being had to the accompanying drawing, forming part hereof, wherein:

Figure 1 is a front view of an aeroplane embodying my improvement;

Fig. 2 is an enlarged longitudinal sectional view of the controller-box and pendulum;

Fig. 3 is a cross sectional view thereof; the section being taken on a line 3—3 in Fig. 2;

Fig. 4 is a diagrammatic view of the electrical circuit for the motor for one of the propellers; and

Fig. 5 is an enlarged sectional detail view of the single acting propeller at the right of Fig. 1.

In the drawing, a bi-plane is indicated by the numeral 4 having the usual aviator's car 5 which carries the motor (not shown) for operating the propeller 6. The power for the motors, which form part of my invention, will be furnished by the storage battery (not shown) with which the modern aeroplane is equipped for self-starting or searchlight purposes.

My improvement comprises propellers 7 and 8, motors 9 and 10 therefor, a pendulum 11, and electric circuits 12 and 13 for the

motors 9 and 10, respectively. A part of each circuit consists of resistances 14 and 15, arms 16 and 17 of the pendulum 11, a brush 18 carried by the pendulum, and a contact 19 located upon but insulated from the controller-box 20. The pendulum 11 includes a weight 21, the function of the pendulum being to cause either the motor 9 or the motor 10 to actuate its respective propeller, should the plane dip to an undesirable extent, by closing the circuit for said motor through the resistances 14 or 15.

As can be seen in Fig. 1, each propeller 7 and 8 is carried by a vertical shaft 22 carrying a bevel-gear 23 meshing with a bevel-gear 24 on the shaft 25 with which each motor 9 and 10 is equipped. The motor 9 is connected to a storage battery 26 (Fig. 4), within the car 5, by the circuit 12, and the motor 10 is connected to said battery 26 by a similar circuit 13. The contact 19 in the box 20 is common to both circuits as well as the brush 18.

Should the plane dip at the end 27 to an undesirable extent, the pendulum 11 would swing to the left, as per arrow 28 in Fig. 2, causing the brush 29, on the pendulum arm 16, to come in contact with the resistance contact 30, which would connect the circuit for the motor 9 through the resistance coils 31 and 32. When thus connected, the motor would rotate relatively slow, thereby operating the propeller 7 to force said end upwardly. Should the said end of the plane continue to dip, the brush 29 would come in contact with contact 33, causing the current to flow through the resistance 32 only. The motor 9, in this event, would rotate at a higher speed, thereby rotating the propeller 7 at a higher speed and exerting more power to right the plane. Should the dip of the plane be dangerously extensive, the brush 29 would come into contact with contact 34, which would cut out all the resistance; hence the propeller would be actuated to the maximum speed. The circuit for motor 10 is the same as above described, and is controlled in a similar manner should the plane dip at the end 35. In this event, the pendulum would swing to the right as per arrow 36, causing the brush 37 to move across the resistance contacts of the controller 15.

By means of the controllers 14 and 15, I am able to cause the stabilizing propellers to rotate at a speed, proportionate to the extent of the dip, and to increase the speed of rotation of the propellers as the dip increases, so that the plane will be righted as rapidly as possible. The controllers 14 and 15 are controlled by the pendulum 11, so that the controllers 14 and 15 will be actuated as the pendulum 11 is actuated by the dip of the plane.

to the dip of the plane; the greater the dip the higher will be the speed of the propeller at the dipping end of the plane.

It will be seen that the controller-box 20 is pivotally connected at 37 and 38 to the aeroplane (in this instance to the lower plane 39) for the reason that I desire to maintain the pendulum in a vertical position regardless of the angular position of the plane longitudinally of the car 5. In other words, by pivotally connecting the controller-box to the plane, the pendulum 11 will hang in a vertical position whether the plane be horizontally positioned, during flight, or inclined upwardly or downwardly; hence the said pendulum will be free to perform its function of controlling the circuits for the motors 9 and 10, as the plane might dip while gliding to the earth or arising therefrom. Brackets 40 and 41 serve as bearing members for the trunnions 42 and 43. The pendulum 11 is mounted on a pivot-pin 44 carried by the box 20, said pin being insulated by a bushing 45 from said box.

The single acting resistances and pendulum are indicated in Fig. 5 by the numerals 48, 49, 50 and 52, respectively. In this form of my invention, each pendulum 52 carries a single arm 53 having a brush 54 to close the circuit between the resistances and contact 55. One of the sets of resistances 48, 49, 50 will be connected to the motor to control a forward speed, and the other a reverse speed. In other words, 46 and 47 are virtually the controller 11 divided into halves.

What I claim as my invention is:

1. In combination with an aeroplane, a controller box pivotally secured thereto, a series of resistances located at each side of the box, a pendulum pivotally connected to said box intermediate said resistances, arms radiating from the pendulum one on each side thereof and extending toward said resistances, a brush carried by each arm and arranged to contact with said resistances, a motor in circuit with each series of resistances, and a stabilizing propeller actuated by each motor.

2. In combination with an aeroplane, a controller box, a stationary contact plate therein, a series of resistances located within the box at each side thereof, a pendulum pivotally connected intermediate its ends to said box between said resistances and below the stationary contact, a brush carried by the upper end of said pendulum in constant engagement with the stationary contact within the box, a pair of radiating arms extending from the sides of the pendulum toward said resistances, a brush carried by each arm and arranged to contact with said resistances, a motor in circuit with each series of resistances, and a stabilizing propeller actuated by each motor.

Signed at New York city, N. Y., this 24th day of October 1917.

ANTHONY CHIARELLI.
